CLAIM

The ornamental design for a light fixture as shown and described.

DESCRIPTION

FIG. 1 is an isometric view of a light fixture.

FIG. 2 is a reverse isometric view of the light fixture shown in FIG. 1.

FIG. 3 is a bottom view of the light fixture shown in FIG. 1.

FIG. 4 is a top view of the light fixture shown in FIG. 1.

FIG. 5 is a front view of the light fixture shown in FIG. 1.

FIG. 6 is a rear view of the light fixture shown in FIG. 1.

FIG. 7 is a left side view of the light fixture shown in FIG. 1; and,

FIG. 8 is a right side view of the light fixture of FIG. 1. The broken lines having equal segments represent portions of the article that form no part of the claimed design. The broken lines having unequal length segments illustrate the boundaries between claimed and unclaimed portions of the design and form no part of the claimed design.

1 Claim, 5 Drawing Sheets
